FLUID PUMP

Milton H. Scherger and Earl B. Terrill, Jr., Chicago, Ill., assignors to Mills Industries, Incorporated, Chicago, Ill., a corporation of Illinois

Application December 12, 1946, Serial No. 715,748

3 Claims. (Cl. 103—44)

1

This invention relates to pumps of the type used for pumping a liquid or other fluid and more particularly to a piston pump in which a diaphragm is employed in conjunction with a body of oil or other hydraulic fluid between the piston and the diaphragm.

An important object of the invention is the provision in such a pump of means for controlling the quantity and condition of the contents of the hydraulic fluid chamber so that the pump will be automatically maintained at maximum efficiency over a long period of time.

To this end provision is made for replacing any liquid that may escape from said chamber and for eliminating any excess liquid or air that may gain admission to the chamber, all without human intervention or the necessity of stopping the operation of the pump to correct any improper conditions.

A further object is to provide a pump for this purpose which is so constructed that the diaphragm will not be subject to as much strain as in the usual diaphragm pump construction and therefore will not require frequent, if any, repair or replacement during the life of the pump.

Another object is to provide a pump without a stuffing box or rotary seal which will nevertheless handle corrosive or valuable fluids automatically without loss of such fluids.

Other objects and advantages of the invention will be apparent from the following description and accompanying drawing in which the single view is a cross section of a fluid pump in which the principles of the invention are embodied.

In the embodiment of the invention shown in the drawing the numeral 11 indicates a crankcase, which preferably is arranged in horizontal position and is supported by an end member 12 having a horizontal portion 13 resting upon any suitable supporting base.

The crankcase is formed to provide a cylinder 14 at one end thereof in which a piston 15 is reciprocably mounted, said piston being connected by the usual connecting rod 16 with a crank 17 on a crank shaft 18 adapted to be driven from any suitable source of power. The crankcase contains a body of oil, indicated by the numeral 19, and when the crankcase is disposed in horizontal position, as shown, the bottom side portion thereof will provide an oil sump in which said oil is contained.

A pump chamber 21 is provided beyond the head of the piston by means of an enlarged cylinder head 22 and a cap 23 secured thereto by screws 24.

2

The outer face of said cylinder head or block 22 is of concave or dished formation, as indicated at 25, and the central part thereof is in the form of a grid having openings 26 therein communicating with the space 21 in the cylinder beyond the head of the piston 15.

The inner face of the cap 23 is also of concave or dished formation, as indicated at 28, the concavity therein complementing the concavity in the cylinder head 25 so as to form a chamber of generally elliptical shape, with the opposed faces thereof sloping gradually from the peripheral portions of the cylinder head and cap, the inner faces of which are preferably flat.

A diaphragm 29 made of rubber sheeting, or other suitable material, is tightly clamped between the peripheral portions of the cylinder head 22 and cap 23 by the screws 24 and extends vertically across the center of the chamber 21 when the piston is in its central position.

The space between the head of the piston 15 and the diaphragm 29 is filled with a suitable hydraulic fluid, such as oil, and the space on the opposite side of the diaphragm is adapted to receive the liquid or other fluid to be pumped.

Such fluid is drawn into the latter space through an intake pipe 31 connecting with an intake check valve 32 communicating with passages 33 extending through the cap 23 into which said check valve is screwed, or otherwise suitably attached. Said valve includes a disc 34 normally held in engagement with a valve seat 35 by means of a spring 36, said valve disc being adapted to be unseated against the tension of said spring when a vacuum is created in the pumping chamber upon the suction stroke of the piston which draws the diaphragm to its innermost position against the face 25.

A discharge check valve 37 is provided in the cap 23 on the opposite side from the intake valve 32 and communicates with an outlet pipe 38. Said discharge valve includes a valve disc 39 normally held against a valve seat 41 by means of a spring 42. Communication is provided between the pumping chamber 21 and the valve 37 by passages 43 extending through the cap 23 and the pumped fluid is forced out through said passages and said discharge valve upon the compression stroke of the piston which unseats the valve disc 39 in obvious manner.

Thus the fluid to be pumped is drawn into the space in the pumping chamber on the outside of the diaphragm 29 on each suction stroke of the piston 15 and is discharged from said space on each compression stroke of the piston, the dia-

phragm being actuated through the medium of the hydraulic fluid in the space between the piston and said diaphragm.

In case of loss of hydraulic fluid from said space by leakage past the piston 15, or otherwise, the lost fluid will be replaced by fluid drawn from the oil sump in the crankcase through a conduit 44 extending from said sump to an oil check valve 45 which in turn communicates with the space 27 through a hole 46 extending radially through the cylinder head 22. Said oil check valve may be of the ball type with a ball 47 normally held against a seat 48 by means of a spring 49. The inner face 25 of the pump chamber limits the inward movement of the diaphragm and, in case of any shortage of hydraulic fluid in the space between the piston and the diaphragm, further movement of the piston on the suction stroke will create a vacuum in said space which will result in the unseating of the valve 47 and the drawing of sufficient oil from the crankcase to completely fill the hydraulic fluid space.

Any loss of fluid from said space can only be between the piston and the cylinder wall, in which case it will be returned to the crankcase so there will be no loss of fluid from the pumping system.

It is possible that some air or excess oil might be drawn into the space between the piston and the diaphragm on the suction stroke of the piston under certain conditions and we provide means for bleeding off such air or excess oil, which means will now be described.

A metering valve 51 is provided in the periphery of the cylinder head 22 and provides intermittent communication between the pumping chamber and the crankcase with which said valve is connected by means of a conduit 52. A passageway 53 leads from the high point in the pumping chamber 21 to a reservoir 54 formed in the cylinder head inwardly from said metering valve 51, and an oil hole 55 extends from the space 27 in the cylinder to said reservoir.

The valve 51 comprises an outer shell 56 screwed into the cylinder head 22 and having plugs 57 and 58 screwed into the interior thereof, with packing rings 59 and 61 interposed between said shell and plugs. A valve seat 62 is provided on the top of the inner plug 58 and a valve seat 63 is provided on the bottom of the outer plug 57. A passageway 64 extends through the plug 58 and the plug 57 has passageways 65 and 66 therein through which fluid may pass when permitted by the action of the valve. A central partition 67 extending horizontally between the walls of the shell 56 has passageways 68 therein and is interposed between two valve discs 69 and 71 carried on a stem 72, which is mounted in a central opening in said partition 67. Said discs 69 and 71 are normally held in their lowermost position by means of a spring 73 mounted on the upper end of said stem 72 and located in a cavity 74 in the plug 57, said spring bearing against a lock nut 75 above the disc 71. The spring thus holds the disc 69 normally in contact with the seat 62, with the disc 71 unseated.

Upon the compression stroke of the piston the valve disc 69 will be unseated and the disc 71 will be seated. Thus as one part of the valve opens the other is moved to closed position, and the reverse action takes place on the return stroke of the piston. On the compression stroke any air or gas collected at the top of the pump-

ing chamber will be forced into the space 54 and, on succeeding strokes, into the space 76 between the two parts of the valve. If no air or gas is present in the top of the pumping chamber a small amount of oil will be bled off on each stroke, the amount not being enough, however, to materially impair the efficiency of the pump.

Since the valve disc 71 will be rapidly seated against the seat 63 only a very small amount of gas or oil (perhaps less than a drop in the case of oil) will be bled on each stroke. The continuous bleeding, however, is sufficient to dispose of any air or oil that may leak past the piston or to purge any air or gas which may be present in the hydraulic fluid chamber when the pump is first put into operation.

It will now be apparent that provision has been made for automatically maintaining the proper quantity and condition of the hydraulic fluid and for preventing undue wear on the diaphragm so that the pump will operate with high efficiency for a long period of time without requiring any servicing or the replacement or adjustment of any of the parts. Furthermore a pump constructed as herein described is adaptable to a wide variety of suction and discharge pressure applications for which previous constructions have not been well adapted.

The foregoing detailed description has been given for clearness of understanding only, and no unnecessary limitations should be understood therefrom, but the appended claims should be construed as broadly as permissible in view of the prior art.

We claim:

1. A pump for liquids or other fluid, comprising a cylinder, a piston reciprocably mounted in said cylinder, a crankcase containing an oil sump and having a crankshaft mounted therein operatively connected with said piston, a pumping chamber beyond the head of the piston, a diaphragm mounted in a midposition in said chamber, the space between the diaphragm and the piston being adapted to receive a hydraulic fluid and the space on the opposite side of the diaphragm being adapted to receive a fluid to be pumped, intake and outlet passages for the pumped fluid communicating with the latter space, a one-way conduit between said hydraulic fluid space and said oil sump whereby oil may be drawn from the latter on the suction stroke of the piston in case of a deficiency in the quantity of the hydraulic fluid in said hydraulic fluid space, and means for bleeding from said hydraulic fluid space upon the compression stroke of the piston, any gas which may accumulate in said hydraulic fluid space, said last-mentioned means comprising a second conduit between the high point in said hydraulic fluid space and said crankcase and a metering valve in said second conduit constructed and arranged to momentarily open on such compression stroke of the piston to bleed a small amount of gas from such hydraulic fluid space on each such stroke.

2. A pump for liquids or other fluid, comprising a cylinder, a piston reciprocably mounted in said cylinder, a crankcase containing an oil sump and having a crankshaft mounted therein operatively connected with said piston, a pumping chamber beyond the head of the piston, a diaphragm mounted in a midposition in said chamber, the space between the diaphragm and the piston being adapted to receive a hydraulic fluid and the space on the opposite side of the diaphragm being

adapted to receive a fluid to be pumped, intake and outlet passages for the pumped fluid communicating with the latter space, a one-way conduit between said hydraulic fluid space and said oil sump whereby oil may be drawn from the latter on the suction stroke of the piston in case of a deficiency in the quantity of the hydraulic fluid in said hydraulic fluid space, and means for bleeding from said hydraulic fluid space upon the compression stroke of the piston, any gas which may accumulate in said hydraulic fluid space, said last-mentioned means comprising a second conduit between said hydraulic fluid space and said crankcase and a metering valve in said second conduit, said metering valve comprising a two-seat valve adapted to momentarily open on such compression stroke of the piston to bleed a small amount of gas from the hydraulic fluid space on each such stroke.

3. A pump for liquids or other fluid, comprising 20 a cylinder, a piston reciprocably mounted in said cylinder, a crankcase containing an oil sump and having a crankshaft mounted therein operatively connected with said piston, a pumping chamber beyond the head of the piston, a diaphragm mounted in a midposition in said chamber, the space between the diaphragm and the piston being adapted to receive a hydraulic fluid and the space on the opposite side of the diaphragm being adapted to receive a fluid to be pumped, intake 30 and outlet passages for the pumped fluid communicating with the latter space, a one-way conduit between said hydraulic fluid space and said oil sump whereby oil may be drawn from the latter on the suction stroke of the piston in case 35

5 10 15

of a deficiency in the quantity of the hydraulic fluid in said hydraulic fluid space, and means for bleeding from said hydraulic fluid space upon the compression stroke of the piston, any gas which may accumulate in said hydraulic fluid space, said last-mentioned means comprising a second conduit between said hydraulic fluid space and said crankcase and a metering valve in said second conduit, said metering valve comprising a movable element having two spaced discs thereon, and a valve block having passageways for the fluid therein, said block having two spaced valve seats adapted to be engaged by said discs, respectively, one thereof being normally seated, one of the discs being unseated when the other is seated and both discs being momentarily unseated upon the compression stroke of the piston whereby a small amount of gas will be bled through said valve upon each such stroke.
